UNITED STATES PATENT OFFICE

DANFORTH K. GANNETT, OF JACKSON HEIGHTS, NEW YORK, ASSIGNOR TO AMERICAN TELEPHONE AND TELEGRAPH COMPANY, A CORPORATION OF NEW YORK

ELECTROOPTICAL SYSTEM

Application filed August 10, 1928. Serial No. 298,758.

This invention relates to electric-optical systems and particularly to an electro-optical image producing system in which one portion of the image is produced in finer detail than another.

An object of the invention is to automatically control the detail with which a given portion of the image is produced.

Another object of the invention is to scan a portion of a field of view in detail to produce an image current for controlling the production of an image and automatically varying the portion of the field of view being scanned.

Still another object of the invention is to automatically vary the portion of the image which is produced in fine detail to correspond with the line of vision of the observer.

There is disclosed in Patent No. 1,624,918 granted to O. B. Blackwell and Joseph Herman, April 19, 1927, a television system in which one portion of the image is produced in finer detail than another portion. A manually operable device is provided for varying the portion of the image which is produced in fine detail. This device may be adjusted by the observer so that the portion of the image toward which his vision is directed is at all times produced in finer detail than the other portions of the image.

In accordance with an embodiment of the present invention shown and described herein, the detail with which a portion of the image is produced is controlled automatically. For this purpose there are provided two banks of long light-sensitive cells, the cells of one bank being arranged horizontally and the cells of the other bank being vertical and positioned in front or in back of the first bank. An image of the pupil of the eye of an observer is focussed on the banks of light-sensitive cells. The cells of each bank are connected to a common circuit in such a manner that the potential drop across a portion of one of the circuits varies in accordance with the vertical position of the image of the pupil of the eye, while the potential drop across a portion of the other circuit varies in accordance with the horizontal position of the image. The potential

variations across these circuits are employed to control the amplitude of the carrier current from two different sources. These carrier currents simultaneously control the position of two lenses, one at the transmitting station and one at the receiving station for controlling the position of the portion of the object which is scanned in fine detail and the position of the corresponding portion of the image which is produced in fine detail.

In another embodiment of the invention a beam of light directed onto the eye of the observer is reflected to the banks of light-sensitive cells. This reflected light impinges on different portions of the banks of light-sensitive cells in accordance with the movement of the eye for correspondingly varying the potential set up across a circuit connected to each bank of light-sensitive elements.

The invention will be readily understood by referring to the following description and the accompanying drawing in which:

Figure 1 is a diagrammatic showing of a transmitting station of a television system; and

Fig. 2 shows diagrammatically a receiving station of the television system.

Referring to Fig. 1 of the drawing, light reflected from the object 10 is passed through a movable lens 11 and thence through the analyzer or scanning mechanism 12. The light which passes through the scanning mechanism is focussed on the light sensitive cell 13 by the lens 14. The scanning mechanism 12 is driven by a suitable driving device such as the synchronous motor 14 and comprises two slotted discs which rotate in such a manner that the opening formed by the intersection of the slots describes a spiral. The scanning mechanism is described in greater detail in the patent to Blackwell and Herman referred to hereinbefore. By means of this scanning mechanism, the object 10 or a portion thereof is scanned along a spiral line. The portion of the object near the center of the spiral is scanned more slowly and hence in greater detail than the portions away from the center. The scanning mecha-

nism may be so designed that the distance between adjacent convolutions of the spiral increases with the distance from the center of the spiral.

5 The quantity of light falling on the light sensitive cell 13 determines a corresponding current to the input of the modulator 15 which is supplied with current of frequency f_1 from the current source 16. Accordingly, this current of frequency f_1 is modulated to correspond to the intensity of the light received from the successively scanned element areas of the object 10. The modulated current passes through the filter 17 and over the line 18 to the receiving station shown in Fig. 2. The power current for the synchronous motor 14 may be an alternating current of 60 cycles per second. A current of frequency f_2 is supplied from the source 21 to the modulator 20 and is there modulated by the alternating current supplied from the source 19. The output of the modulator 20 goes through the filter 22 and is also put on the line 18 along with the current of frequency f_1 modulated according to the light actuating the light sensitive cell 13.

At the receiving station shown in Fig. 2 the modulated currents of basic frequencies f_1 and f_2 go, respectively, to the appropriately designed filters 23 and 24 and thence respectively to detectors 25 and 26 whose output circuits carry currents corresponding to the modulated currents produced at the transmitting station. The amplifier 27 receives current of the same frequency as that supplied from the source 19 to the synchronous motor 14 and thus the amplified output current from the amplifier 27 drives the synchronous motor 28 at the same speed as the motor 14 is driven, 40 and the scanning device 29 at the same speed as the scanning device 12. The scanning device 29 is a duplicate of the device 12, having an opening formed by the intersection of two slots, and this opening describes a spiral course rapidly repeated in synchronism with the spiral traversed at the sending end. Light from a determinate portion of the source 30 goes through the light valve 31 to the opening in the device 29 and is focussed by the lens 32 in a small spot on the screen 33. This spot describes a spiral and at each point of this spiral the degree of illumination is determined by the light valve 31 in correspondence with the degree of 45 illumination of a corresponding elemental area of the object 10 at the transmitting station. Since the spirals are repeated 16 or more times per second, an observer looking at the screen 33 sees an image of the object and, if 50 there is motion in the object, he sees the motion.

When a person views an object or objects having motion, he ordinarily fixes his attention and directs his gaze on a small central 55 region of his entire field of view and receives

this narrow region very distinctly and all the outlying portions of his field of view is comprehended less distinctly. Moreover, when there is motion within the field of view the observer will be likely to shift the narrow region of closest attention according as the motion causes his interest or concern to change from one place to another.

An image 70 of the pupil of the eye of an observer is focussed on two banks of long 75 light sensitive cells, the cells 34 of one bank being arranged horizontally and the cells 35 of the other bank being vertical and in front of the first bank. The portions of the banks of light sensitive cells surrounding the image 80 of the pupil of the eye formed thereon are illuminated by light reflected from the portion of the eye surrounding the pupil and from the face of the observer. As the observer moves his eyes so as to observe different portions of the image formed on the screen 33, the image of the pupil of one of his eyes formed on the banks of light sensitive cells 34 and 35 correspondingly changes in 85 position. The light tone value of the pupil 90 of the eye corresponds to black while the surrounding portions of the eye and the face are of relatively light tone value. The light sensitive cells are preferably so arranged 95 that the image of the pupil of the eye covers a portion of one of the vertical cells and one of the horizontal cells. The impedance of the cells on which the image of the pupil of the eye is focussed is greater than the impedance 100 of the remaining cells and the current through the first mentioned cells is correspondingly decreased. One terminal of each of the horizontally arranged cells 34 is connected to one terminal of battery 36, while the other terminal of each cell is connected to a terminal of one of the resistance elements 105 37 which are connected in series. An end terminal of the group of resistance elements is connected to the other terminal of battery 36. In a similar manner one terminal of each of the vertical cells is connected to one terminal of the battery 38, while the other terminal of each cell is connected to a terminal of one of the groups of series connected resistance elements 39. One end terminal of this 110 group of resistances is connected to the other terminal of battery 38. The resistance elements 37 and 39 are preferably of equal value. The group of resistance elements 37 is connected in series with the biasing battery 115 40 and the secondary winding of transformer 41 to the control electrode and cathode, respectively, of vacuum tube modulator 42. A source of current of frequency f_3 is connected to the primary winding of transformer 41. The anode circuit of modulator tube 42 is connected to the primary winding of transformer 43, the secondary winding of which is connected to the band pass filter 44. The end terminal of the group of resistance ele- 120 125 130

ments 39 is similarly connected through biasing battery 45 and primary winding of transformer 46 to the control electrode and cathode, respectively, of modulator tube 47. The secondary winding of transformer 46 is connected to a source of current of frequency f_4 . The anode circuit of modulator tube 47 is coupled through transformer 48 to the band pass filter 49.

It is apparent from an observation of the circuit arrangement, that when each of the similar cells 34 and 35 is equally excited by light, the internal resistances of the cells are equal. When an image of the pupil of the eye is formed on several of the cells, the resistance of each of these cells increases and the potential differences across the group of resistance elements 37 and across the group of resistance elements 39 correspondingly decrease. The decrease in potential drop across the group of resistance elements 37 is greatest when the image is formed on the upper light sensitive cell as viewed in the figure and least when formed on the lowest cell of the group. Similarly, the decrease in voltage across the group of resistance elements 39 is greatest when the image of the pupil of the eye is formed on the cell toward the right as viewed in the figure. The potential applied to the control electrode of the modulator vacuum tube 42 is thus determined in accordance with the vertical position of the image of the pupil of the eye, the higher the image the smaller the potential applied to the control electrode. In a similar manner the potential applied to the control electrode of the modulator vacuum tube 47 decreases as the image of the pupil of the eye moves to the right as viewed in the figure. Accordingly the current of frequency f_3 leaving the filter 44 has an amplitude which varies in accordance with the vertical position of the image of the pupil of the eye, while the current of frequency f_4 leaving the filter 49 has an amplitude which varies in accordance with the horizontal position of the image.

The current leaving the filter 44 is detected by the detector 50, the uni-directional output current of which goes to the movable coil 51 which is in the magnetic field produced by the direct current in the winding 52. The arm 53 carried by the movable coil 51 is adapted to shift the lens 32 in a vertical direction as viewed in the figure. The current leaving the filter 49 after being detected by the detector 54 goes through the movable coil 55 which is in the magnetic field produced by the direct current in winding 56. The arm 57 carried by the coil 55 is adapted to control the movement of the lens 32 in a direction perpendicular to the plane of the drawing, the coil 55 being turned to facilitate its showing in the diagram.

The currents of frequencies f_3 and f_4 leaving the filters 44 and 49, respectively, are also

transmitted over line 18 to the transmitting station where they are separated by filters 58 and 59 and then go to the detectors 60 and 61, respectively. The uni-directional output currents from these detectors correspond to the output currents of detectors 50 and 54, respectively. These output currents act upon the coils 62 and 63, respectively, to control the position of the lens 11 in accordance with the position of the lens 32.

As the observer directs his attention to different portions of the image formed on the screen 33, the position of the image 70 of the pupil of his eye formed on the banks of light sensitive cells 34 and 35 shifts correspondingly. As a result the currents leaving the filters 44 and 49 vary correspondingly and determine the position of the lenses 11 and 32. The positions of these lenses in turn determine the portion of the object 10, which is scanned in fine detail and the corresponding portion of the image formed in fine detail on the screen 33, this portion of the image being the one to which the attention of the observer is directed.

Instead of focussing an image of the pupil of the eye of the observer on the banks of light sensitive cells, a small beam of light may be reflected from the eyeball of the observer onto the banks of light sensitive cells. Since the eyeball is not perfectly spherical in shape the position of the beam as it reaches the banks of light cells varies in accordance with the direction in which the observer is looking.

The range of frequency components of the current transmitted for producing the image is limited by the transmission characteristics of the transmission channel. If, instead of scanning a portion of the field of view in fine detail and another portion in less detail as in the system disclosed herein, the entire field of view be scanned in fine detail, it would be necessary to transmit an image current having a relatively wide range of frequency components or otherwise to decrease the size of the image produced. If it be desired to produce a large image of a field of view which is scanned uniformly by transmitting the image current over a channel capable of transmitting only a relatively narrow band of frequencies, the image will be produced in poor detail. It is thus apparent that the frequency range which can be transmitted over a channel is utilized to the best advantage when a portion of the image to which the observer directs his attention is produced in fine detail and the surrounding portions of the image are produced in less detail.

What is claimed is:

1. The method of producing an image electro-optically, which comprises scanning a portion of a field of view in detail to produce an image current, impressing said current on a device for producing an image of the portion of the field of view being scanned, and

automatically varying the portion of the field of view being scanned.

2. The method of producing an image electro-optically, which comprises scanning a portion of a field of view in fine detail, scanning another portion of the field of view in less detail, producing an image current as the result of said scanning, utilizing said image current to control the production of an image in accordance with said scanning, and automatically varying the portion of the field of view which is being scanned in fine detail.

3. An electro-optical image producing system, comprising means for scanning a field of view to produce an image current, said means being adapted for scanning one portion of the field of view in finer detail than another portion thereof, means responsive to said image current for producing an image of said field of view, the detail of different portions of which is controlled in accordance with said scanning, and means for automatically varying the portion of the field of view which is scanned in fine detail as the observer directs his vision toward different portions of the image.

4. An apparatus for controlling the position of an element in accordance with the movement of the eye of an observer which comprises a group of light sensitive cells, and means for varying the impedance of at least one of said cells in accordance with the movement of the eye of said observer.

5. An apparatus for controlling the position of an element in accordance with the movement of the eye of an observer which comprises an electric circuit, a plurality of light sensitive cells connected to said circuit, and means including said light sensitive cells for controlling the voltage drop across at least a portion of said electric circuit in accordance with the movement of the eye of said observer.

6. An apparatus for controlling the position of an element in accordance with the movement of the eye of an observer which comprises a bank of light sensitive cells, and means for causing light reflected from the eye of the observer to reach said bank of light sensitive cells for controlling the impedance of different cells in accordance with the movement of the eye of said observer.

7. In an electro-optical image producing system, means for scanning a field of view to produce an image current, means for utilizing said image current for producing an image of said field of view, and means for shifting the field of view being scanned in response to the movement of the eye of an observer.

8. In an electro-optical image producing system, means for scanning a field of view to produce an image current, means for utilizing said image current for producing an image of said field of view on a screen, and

means for shifting the field of view being scanned in accordance with the portion of the screen toward which the observer directs his line of vision.

9. In an electro-optical system, a plurality of light sensitive cells, means for varying the light actuation of said cells for controlling a characteristic thereof, and means controlled in accordance with a varying characteristic of said cells for controlling the position of a movable element over a range of positions between fixed limits.

10. In an electro-optical system, two banks of long light sensitive cells, the cells of one bank being positioned so that their longitudinal axes form an angle with the longitudinal axes of the cells of the other bank, two groups of series connected resistance elements, one group being associated with each bank of light sensitive cells, an electrical connection from each light sensitive cell to a terminal of a different resistance element, means for directing light from the eye of an observer onto said banks of light sensitive cells for controlling the potential drops across said groups of resistance elements, a device which is to be moved in accordance with the movement of the eye of said observer, and means responsive to the potential drops across said groups of resistance elements for controlling the position of said device.

In testimony whereof, I have signed my name to this specification this 9th day of August, 1928.
